UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

BAG-FASTENER.

1,153,301.

Specification of Letters Patent. Patented Sept. 14, 1915.

Application filed January 24, 1914. Serial No. 814,063.

To all whom it may concern:

Be it known that I, FRANZ A. FULLER, a citizen of the United States, residing in the city of Newark, in the county of Essex 5 and State of New Jersey, have invented certain new and useful Improvements in Bag-Fasteners, of which the following is a full, clear, and exact description, such as will enable others skilled in the art to which it pertains to make, construct, and use the same, reference being had to the accompanying drawings, and to numerals of reference marked thereon, forming a part of this specification.

15 In the use of bags, pocket books, and the like, much difficulty has been encountered in overcoming the objection raised by those who use such articles, to the spreading of the bag frame members when the contents 20 of such bag or pocket book are such as to so distend the sides as to make the closing of the bag or pocket book difficult. The principal objection arises from the fact that as 25 ordinarily constructed, but a single catch or lock is provided in the center of the bag frame members for holding the same together, leaving the ends of the frame to be sprung apart by overcrowding the interior 30 of the bag, with resulting annoyance and loss. In order to eliminate these evils and 35 overcome these objections, I have devised a new fastener which holds the bag frame members together and which is further provided with an auxiliary catch secured to the 40 said fastener for additionally holding the members together and independently operated from the fastener.

In carrying out my invention, I make use 45 of the structure illustrated in the accompanying drawings, in which—

Figure 1 represents a perspective view of a bag frame having applied thereto, in locked position, my improved bag fastener. Fig. 2 represents an enlarged side elevation, 45 in unlocked position, of my improved fastener. Fig. 3 represents a side elevation in section and in locked position of my improved fastener. Fig. 4 represents a plan view; and Fig. 5 represents a transverse section of the same taken on lines $x-x$ of Fig. 4 and looking in the direction indicated by the arrow.

Similar numerals of reference refer to like parts throughout the specification and 55 drawings.

A bag frame fastener made in accordance with my invention, may be applied to any ordinary or desired form of frame. That shown in the drawings, consists of two hinged members 1 and 2 of substantially the 60 shape shown in Fig. 1. Near the middle portion of the frame member 1, I secure the fastener or catch substantially as illustrated in Fig. 4 of the drawings, or in any other 65 convenient or desired manner.

3 represents a plate secured to the frame member 1, preferably by means of two rivets 4 inserted through apertures formed in the frame member 1, and clenched over in any suitable or convenient manner, thereby serving 70 to secure the plate 3 with the catch or locking members 5 and 6 to the frame member 1. Integrally formed on the ends of the plate 3 and extending beyond one side thereof are bearings 7 and 8, formed by curling 75 the metal of said plate, the bearings being designed to support the locking members 5 and 6, and to be embraced by the extensions formed thereon. The catch 5, preferably 80 consists of an open-ended casing provided with two downwardly extending sides 9 and 10, designed to embrace and hold the frame members 1 and 2 together. Extending rearwardly from the sides 9 and 10 of the catch member 5, are extensions 11, by means of 85 which the said catch member 5 is hingedly secured to the integral bearing 7 formed on one end of the plate 3 by means of the pin 12. Both of the downwardly extending sides 9 and 10 of the catch member 5, are adapted 90 to snap over pressed-out portions 13, which are preferably merely projections from the metallic bag frame members, as clearly shown in Fig. 5 of the drawings. This prevents an accidental removal of the catch 95 member 5.

The locking member 6 preferably consists of an open casing designed to embrace the upper portion of the catch member 5. Extending rearwardly from the sides of the locking member 6, are extensions 14, by means of which the said locking member is 100 hingedly secured to the integral bearing 8 formed on the opposite end of the plate 3 by means of the pin 15. Formed centrally 105 and preferably integrally with one end of the locking member 6, is an inwardly extending projection 16, designed to have locking engagement with the under side of the bearing 7 formed on the plate 3, so that 110

when the locking member 6 is in its locked position and embracing the catch member 5, such projection 16 will have locking engagement with the bearing 7 and the extensions 5 11 of the catch member 5 and firmly secure the catch and locking members in locked position.

It will thus be seen that I have provided an inexpensive bag fastener, simple in construction, attractive in appearance, in which I have reduced the actual number of parts to a minimum, and that when assembled and in position, the possibility of the parts becoming separated by careless manipulation, 15 have also been reduced to a minimum.

Experience has demonstrated that the organization above described is a highly efficient one, and while I have shown the preferred embodiment of my present invention, 20 I do not wish to be limited to the exact details of construction, combination and arrangements herein set forth; it being obvious that minor variations thereof not involving the exercise of invention, may be made by any skilled mechanic, and such departures from my structure not involving invention, I consider within the scope and terms of my claims.

I claim:

- 30 1. In combination, two members movable relatively to each other, a fastener secured to one of said members embracing and holding said frame members together, and a locking device secured to one of said members having locking engagement with said fastener for additionally holding said fastener and members together and independently operated from the fastener.
- 35 2. In combination, two members movable relatively to each other, a fastener secured to

one of said members embracing and holding said frame members together, and an encircling locking member pivotally mounted on one of said members and adapted to encircle said fastener and provided with means for 45 resisting the application and removal of said encircling member from around said fastener.

3. In combination, two members movable relatively to each other, a plate located on 50 one of said members, a fastener pivotally secured to one end of said plate embracing and holding said frame members together, and a locking device pivotally secured to the other end of said plate, said locking device 55 having locking engagement with said fastener for additionally holding said fastener and members together and independently operated from said fastener.

4. In combination, two members movable 60 relatively to each other, a plate provided with integral end bearings secured to one of said members, a fastener comprising an open ended casing pivotally secured to one of said end bearings and embracing and holding 65 said frame members together, and an encircling locking device pivotally secured to the other end bearing, said locking device designed to encircle and have locking engagement with said fastener for additionally 70 holding said fastener and members together and independently operated from said fastener.

This specification signed and witnessed this 19th day of January, 1914.

FRANZ A. FULLER.
